COMBINED WATER HEATER LATERAL FLOW RELIEF VALVE AND UNION

Jack A. Britton, Lakewood, Ohio

Application September 22, 1955, Serial No. 38,051

Term of patent 14 years

(Cl. D78—1)

Fig. 3

Fig. 1

Fig. 2

Fig. 1 is a side elevational view of a combined water heater lateral flow relief valve and union showing the design;

Fig. 2 is an elevational view of the right end of the valve and union shown in Fig. 1; and

Fig. 3 is a top view of the valve and union.

The dominant features of the present design reside in the portions shown in full lines.

I claim:

The ornamental design for combined water heater lateral flow relief valve and union, substantially as shown and described.
